UNITED STATES PATENT OFFICE.

FRANCIS W. JOHNSTONE, OF FORT SMITH, ARKANSAS.

ENGINE.

1,280,484.

Specification of Letters Patent.

Patented Oct. 1, 1918.

Application filed February 16, 1918. Serial No. 217,478.

To all whom it may concern:

Be it known that I, FRANCIS W. JOHNSTONE, of Fort Smith, in the county of Sebastian and State of Arkansas, have invented a certain new and useful Improvement in Engines, of which improvement the following is a specification.

My invention relates, generally, to engines operated by fluid pressure, but is particularly adapted for application as an internal combustion engine, in which oil or gas may be used as fuel. It is also specially designed to operate as a locomotive engine, in which case it may be coupled directly to the driving wheels of the vehicle or may be connected to drive an electric generator, which, in turn, supplies the current for operating electric motors mounted on the axles.

One of the objects of my invention is to provide a substantially perfectly balanced engine, in which all of the moving parts are counterbalanced by other moving parts, so as to eliminate practically all vibration and produce a smooth running machine. Another object is to provide a compact and efficient construction which may be built in large sizes, up to two thousand horse power or more, and yet be contained within the usual clearance limits of the standard locomotive.

Under my invention, the construction includes upright cylinders disposed in pairs, one or more, with a rocking beam pivoted above each pair of cylinders, and connected by rods at opposite ends, with the pistons, and a main crank shaft below the rocking beam, between the cylinders, and a connecting rod from each rocking beam to a corresponding crank on the main shaft.

While my improved engine may be operated by steam or gas, it is particularly adapted to be employed as an internal combustion engine for locomotives, and it is so illustrated in the accompanying drawings, in which:

Figure 1 is a side view, in elevation, of the locomotive with a portion broken away to show the engine; Fig. 2, a transverse section of the locomotive upon a larger scale, showing the engine partially in end elevation and partially in vertical section through the center of one of the cylinders, and, Fig. 3, a longitudinal sectional view of the engine, one half being taken on a central vertical plane, and the other half partly on said plane

and partly on a vertical plane through the center of one of the cylinders.

As shown more particularly in Figs. 2 and 3, my improved engine construction comprises cylinders 4, arranged in pairs, one or more being used as desired, and set in a vertical or upright position with their upper ends open, the pistons, 5, of each pair of cylinders being connected by means of rods, 6, with the opposite ends of a rocking beam, 7, mounted to oscillate on a fulcrum or trunnion shaft, 8, supported above and substantially midway between the cylinders. The main driving or crank shaft, 9, is located below and at right angles to the rocking beams, and between the cylinders, and is driven by a main connecting rod 10, pivotally connected to each rocking beam, at a point between its fulcrum and one end, and connected, at its lower end, to the pin, 11, of a corresponding crank on said shaft.

This construction has the advantage of being very compact and occupies a minimum amount of space laterally and vertically, even when built in large power units. It is also substantially perfectly balanced, as the pistons and their rods at opposite ends of the rocking beam exactly balances each other, and the upper portion of the main connecting rod 10, which may be regarded as a reciprocating part, is balanced by the weight cast in the beam upon the opposite side of the fulcrum, (indicated in dotted lines in Fig. 2). The lower portion of the main connecting rod, which may be regarded as a revolving weight, is balanced by counterweights carried on the inside end of the crank arms or by similar parts on an adjacent crank set at 180°, where a plurality of pairs of cylinders are employed. With this construction also, the angularity of the piston connecting rods is so slight that there is practically no side thrust of the pistons against the walls of the cylinder, thus further reducing vibration and increasing the efficiency of the engine. A comparatively long main connecting rod may also be used with this construction, which is a decided advantage.

In the larger power engines, where more than one pair of cylinders are employed, the rocking beams are preferably disposed in parallel planes or side by side, with their fulcrums substantially in line with each other upon a common axis, and the main

driving shaft is provided with a plurality of cranks corresponding to the number of pairs of cylinders, the cranks being preferably symmetrically located, that is, in the case of two, they would be spaced 180° apart; in the case of three, 120° , etc., thus producing a balance for the rotating parts.

Where my improved engine is employed for propelling a locomotive, the cylinders 10 may be mounted in an upright position upon a suitable floor or frame 21, of the locomotive, the cylinders of each pair being located upon opposite sides of the longitudinal center line of the locomotive, and with the main 15 driving or crank shaft substantially on the center line between said cylinders. By means of this arrangement, the construction occupies a minimum amount of space vertically and laterally, so that by using a 20 plurality of pairs of cylinders, engines of comparatively large power may be installed within the usual clearance limits allowable for a locomotive. The main crank shaft may be connected to drive an electric generator 12, which supplies the current to 25 operate motors mounted on the axles, in the usual well known manner. The engines may be duplicated upon an extension of the main shaft at the opposite side of the electric generator, where greater power is desired, 30 as will be readily understood.

With this construction having a comparatively low center of gravity, and its balanced moving parts symmetrically located relatively to the longitudinal center line of the 35 locomotive, there will be very little vibration, oscillation, or rolling effect, and a perfectly steady and smooth running engine is obtained.

40 For operating the engine by internal combustion with gas or oil as fuel, suitable valves 13, are located at the bottom ends of the cylinders, said valves having stems 14, operated by levers 15, rods 16, and cams 17, 45 mounted on the cam shafts 18, which may be driven from the crank shaft by means of sprockets 19, and chains 20. It will, however, be apparent that any other suitable or preferred form of valve mechanism

may be employed and that the engine may 50 be operated by steam or other fluid pressure if desired.

I claim as my invention and desire to secure by Letters Patent:

1. The combination with the floor frame 55 of a locomotive, of an engine comprising a pair of vertical cylinders open at their upper ends and bolted upon said frame one on each side of the longitudinal center line of the locomotive, a crank shaft journaled between said cylinders in the vertical plane of said line, a fulcrum shaft in said plane above the upper ends of said cylinders, a rocking beam on said fulcrum shaft, connecting rods between the pistons of said 60 cylinders and the ends of said beam, and a connecting rod pivotally connected to said beam between its fulcrum and one end and to said crank shaft.

2. A prime mover for locomotives, comprising the combination with a crank shaft mounted in the central vertical plane of the locomotive, operative connections therefrom to the wheels, a plurality of pairs of upright cylinders mounted on opposite sides of said 65 shaft, a walking beam mounted to oscillate above each pair of cylinders, rods connecting the pistons of each pair of cylinders to the ends of the corresponding beam, and a connecting rod pivotally connected to each 70 beam between its ends and to the corresponding crank on said crank shaft.

3. In an electric locomotive, the combination with the bed-plate or frame, of a main crank shaft journaled centrally thereon, an 75 electric generator coupled to said shaft, a fulcrum shaft mounted on said frame above said crank shaft, a pair of cylinders bolted on said frame one on each side of said crank shaft, a rocking beam mounted on said fulcrum shaft above said cylinders, a piston in each cylinder, a rod connecting each piston to the corresponding end of said beam, and a 80 rod connecting said crank shaft to said beam.

FRANCIS W. JOHNSTONE.
